VALVE FOR PNEUMATIC ENGINES

Albert W. Arnold, Charlotte, N. C.

Application February 3, 1930, Serial No. 425,574

6 Claims. (Cl. 121—164)

This invention relates to a pneumatic engine and more especially to a combination of means to impart reciprocating movement to a member, said member being adapted to have secured thereto any suitable work performing means.

An object of my invention is to provide a pneumatic engine adapted to operate quickly and having means for regulating the speed of operation of said pneumatic engine.

Another object of my invention is to provide a pneumatic device for imparting reciprocating movement to a work performing member with means for securing any desired work performing means to said work performing member.

Another object of my invention is to provide a pneumatic device having means for controlling the same together with special features incorporated therein as will more fully appear as the description proceeds.

Some of the objects of my invention having been stated other objects will appear as the description proceeds, when taken in connection with the accompanying drawings, in which—

Figure 1 is a side elevation of my device with parts thereof broken away;

Figure 2 is a view taken along the line 2—2 in Figure 1;

Figure 3 is a cross-sectional view taken along the line 3—3 in Figure 1;

Figure 4 is a view taken along the line 4—4 in Figure 2;

Figure 5 is a longitudinal cross-sectional view through the piston;

Figure 6 is a view taken from a point along the line 6—6 in Figure 2;

Figure 7 is an exploded perspective view of the valve mechanism and associated parts.

Referring more specifically to the drawings the numeral 10 indicates the base of my device which has the holes 11 and 12 therein for securing the same to any suitable means of support, and projecting upwardly is a portion 13 which has on the upper end thereof and integral with the portion 13, a casing 14 in which my valve mechanism is housed. Integral with the portion 14 and projecting from one side thereof is a piston casing 15, though it is apparent that this casing 15 might be made separate if desired. This portion 14 has the transversely disposed bore therein in which the valve member 16 is rotatably mounted, said valve member comprising the enlarged flange portion 17 and a projecting threaded portion 18 on the other end thereof, which portion 18 is adapted to have secured thereto nuts 19 by means of which the valve can be secured in the casing.

The portion 15 has a hole 20 therein which registers with a chamber 21, in which a piston 22 is mounted. This piston 22 has the packing 23 secured thereon by means of a washer 24 held in place by screw 25. This piston 22 has a hollowed out portion 26 and in the base of this hollowed out portion 26 as at 27 is secured a rod 28 by being threadably secured into the piston 22 as at 27 with a collar 29 thereon to limit its inward movement. This rod 28 is threaded as at 30 at its other end, and is adapted to have any suitable work performing means secured thereto, the purpose of the whole mechanism being to reciprocate rod 28 back and forward at any desired speed.

The rod 28 has secured thereon a downwardly projecting arm 32 which has pivotally connected at its lower end by means of bolt 33, the rod 34 which is connected by means of bolt 35 to an arm 36 which projects downwardly from a disk 37. This disk 37 has a hole 38 therein which is adapted to receive the pin 18 on the valve member 16, and this disk 37 also has the inwardly projecting pin 38a which is adapted to work in slot 39 of disk 40, said disk 40 having a hole 41 therein, which is also adapted to work on the pin 18. This disk 40 has another arc-shaped slot 42 therein, in which a pin 43 which is securely mounted in the valve member 16 is adapted to work. This pin 43 is adapted to cooperate with the entire mechanism as will be later described. This disk 40 has notches 45 and 46 therein with the tooth 47 rising up between said notches with sloping shoulders 48 and 49 with the flat portion 50 on top or at the end portion of said tooth.

The valve member 16 has a port 60 passing all the way therethrough in a direction transverse to the axis of the valve member and in a direction which is longitudinal with relation to the bore 21 of the cylinder 15. This port has at its outer end, grooves 61 which run on the surface of the member 16 in a parallel relation to the projection 18 and circumferential grooves 62 and 63 communicating with the outer ends of grooves 61 are provided for the purpose of distributing throughout the circumference of the valve the pressure of groove 61.

The port hole 65 also is provided in the valve member which is in the same transverse plane of the valve member 16, said hole 65 penetrating from the exterior of the valve member 16 and running toward the center thereof, but stopping short of the center thereof and registering with a channel or hole 66 which is located in a parallel relation to the pin 18, this hole 66 running

to the exterior of the valve on the end of the valve on which the enlarged flange 17 appears, and this hole 66 is enlarged as at 67 into which a needle valve 68 is adapted to be mounted by means of threadably engaging the arm 69 and being adjusted in position by means of a nut 70, said arm 69 being secured by means of bolt 71 to the valve member 16.

The member 32 is adjustably secured along the rod 28 by means of a set screw 73, so that by adjusting the position of the member 32 the throw of the valve can be regulated.

Projecting upwardly from the top of the casing 15 is a projection 75 which has a bolt 76 therein, on which is pivotally mounted the member 77 which has a hole 78 intermediate its ends through which a bolt 79 passes loosely, the lower end of said bolt being threadably secured in the projection 81 on the casing 15, and above the member 77, and between a washer 82 on the upper end of the bolt is a compression spring 83 which is adapted to normally force the member 77 downwardly. On the free end of the member 77 there is provided the enlargement 85, which is pointed on its lower end, and is adapted to rest in one of the notches 45 or 46 as the case may be, and to assist in the operation of the valve mechanism.

In the other side of the valve casing 14 opposite from the point at which the projection 15 emanates is a projection 96 which has the passageway 87 therethrough registering with the port hole in said valve mechanism, and this is threaded on its interior to receive any desired source of fluid supply.

The cylinder 15 has a cap 90 threadably secured on the open end thereof which cap 90 has a plurality of holes 91 therein to allow air to pass readily therethrough in both directions, and the bushing 92 is secured in a central opening in said cap, in which bushing the rod 28 is slidably mounted, and around the rod 28 between bushing 92 and the closed end of the cylinder 22 there is mounted the compression spring 93, the purpose of said compression spring being to return the piston to the right in Figure 1 after it has been driven to the left by air passing into the chamber 21.

The method of operation of my device is as follows:

With the parts in the position shown in Figure 1 air pressure is admitted through the passageway 87 through port 60 and hole 20, and into the chamber 21 which forces the piston 22 to the left hand in Figure 1 and this forces the rod 28 to the left hand, and along with it is carried the arm 32 which likewise carries the rod 34 and turns disk 37 mounted on pin 18 and the pin 38a on disk 37 is resting normally at the point c in slot 39 and pin 43 is normally resting at the point b in slot 42, and as the piston is moved to the left in Figure 1 the pin 38a rotates disk 40 in a clockwise direction, and this continues until the pin 43 in the valve 16 rests at the point a in slot 42, and as disk 37 is rotated pin 38a engages end c of slot 39 and at this time disk 40 is moved and the portion 85 of member 77 is raised upwardly by the sloping surface 49 and causes the other side of the sloping surface of member 85 to engage the sloping surface 48 of the projection 47 and the compression spring 83 forces member 77 downwardly which carries with it the projection 85, and this quickly forces the further turning of disk 40 and valve member 16 to cause the port hole 20 to cease to register with the hole 60

running through the valve but causes the hole 20 to register with the port hole 65 which communicates with passageway 66 which allows escape of the fluid from chamber 21 through passageway 66 out past the needle valve 68 at the end of passageway 66, and the fluid escaping through this needle valve causes the compression spring 93 to return the parts to original position as is shown in Figure 1. The return of the parts to original position is accomplished by arm 32 and rod 34 moving to the right in Figure 1 along with piston 24, and rod 34 turns disk 37 in a counter-clockwise direction and this causes pin 38a to move into end d of slot 39 in disk 40 and turns disk 40 also in a counter-clockwise direction to cause projection 47 to ride beneath member 85 as member 85 is raised upwardly by surface 48 and then member 85 rides down surface 49 and moves disk 40 after movement of disk 37 ceases, and this further movement of disk 40 causes the parts to assume the position shown in Figure 1, and at this point air pressure is again admitted to chamber 21 as above described. The length of stroke of piston 24 is that required to raise arm member 85 to a point where it is ready to travel down cam surface 48. This operation can be repeated very quickly, in fact can occur several hundred times within a minute, and one operation as above described fully sets forth the method of operation which is repeated. By adjusting needle valve 68 the rate of flow of the escaping fluid is governed and thereby the rate of speed of the device is regulated.

In the drawings and specification I have set forth a preferred embodiment of my invention, and although specific terms are employed they are used in a generic and descriptive sense only, and not for purposes of limitation, the scope of the invention being set forth in the appended claims:

I claim:

1. Valve mechanism comprising a valve casing having a cylinder therein with aligned openings in opposite sides thereof, a solid valve rotatably mounted in said cylinder, said valve having a straight cylindrical bore extending transversely through the axis thereof and communicating with the periphery of the valve only at the opposite ends of said bore, said bore being arranged to communicate with the cylinder openings, said valve having a radial bore therein extending throughout its length toward the transverse bore and disposed wholly in a transverse plane extending through the transverse bore, said valve having a longitudinal bore disposed eccentrically thereof and extending in a straight line from the inner end of the radial bore to an end of the valve.

2. Valve mechanism comprising a valve casing having a cylinder therein with aligned openings in opposite sides thereof, a solid valve rotatably mounted in said cylinder, said valve having a straight cylindrical bore extending transversely through the axis thereof and communicating with the periphery of the valve only at the opposite ends of said bore, said bore being arranged to communicate with the cylinder openings, said valve having a radial bore therein extending throughout its length toward the transverse bore and disposed wholly in a transverse plane extending through the transverse bore, said valve having a longitudinal bore disposed eccentrically thereof and extending in a straight line from the inner end of the radial bore to an end of the valve, and means carried by the last-mentioned

end of the valve for regulating the opening through said longitudinal bore.

3. Valve mechanism comprising a valve having a longitudinal bore therein extending to an end of the valve, an arm secured to said end of the valve, and a needle valve having screw-threaded connection with and carried by said arm and extending lengthwise relative to an end of the longitudinal bore for regulating said bore.

4. Valve mechanism comprising a valve having a longitudinal bore extending to an end of said valve, an arm carried by said end of the valve and extending in overlapping and spaced relation with the end of the longitudinal bore, and a needle valve threaded through said arm and into an end of the longitudinal bore for regulating said bore.

5. Valve mechanism comprising a valve casing having openings in different sides thereof, a valve rotatably mounted in the casing and having a transverse bore therein in position to register with and connect said openings, said valve

having a radial bore in position to register with at least one of said openings, and having a longitudinal bore extending from said radial bore to an end of the valve, said last-mentioned end of the valve and of the longitudinal bore projecting outside of and being uncovered by the casing, an arm secured to said end of the valve, and a valve having screw-threaded connection with and carried by said arm and extending into position for regulating the longitudinal bore. 10

6. Valve mechanism comprising a casing, a valve rotatably mounted therein, said valve having a transverse bore therein, and having a longitudinally extending groove in the periphery thereof communicating with said transverse bore, and said valve having one or more circumferential grooves in the periphery thereof communicating with said longitudinally extending groove for distributing the pressure of said longitudinal groove about the periphery of the valve. 15 20

ALBERT W. ARNOLD.
